UNITED STATES PATENT OFFICE.

FRANK HARTLEY ANDERSON, OF BIRMINGHAM, ALABAMA.

DESIGN FOR A STATUETTE.

Application filed August 16, 1928. Serial No. 27,837. Term of patent 3½ years.

To whom it may concern:

Be it known that I, FRANK HARTLEY ANDERSON, a citizen of the United States, residing at Birmingham, in the county of Jefferson and State of Alabama, have invented a new, original, and ornamental Design for a Statuette, of which the following is a specification, reference being had to the accompanying drawings, forming a part thereof.

Fig. 1 is a front view of the statuette showing my new design; and

Fig. 2 is a side view thereof.

I claim:

The ornametal design for a statuette substantially as shown.

In testimony whereof, I, FRANK HARTLEY ANDERSON, affix my signature.

FRANK HARTLEY ANDERSON.
